DESIGN FOR A COMBINED BILLFOLD, KEY CASE, AND TOKEN PURSE

Milton Becker, Passaic, N. J.

Application March 3, 1944, Serial No. 112,779

Term of patent 14 years

(Cl. D87—3)

To all whom it may concern:

Be it known that I, Milton Becker, a citizen of the United States of America, residing at Passaic, county of Passaic, and State of New Jersey, have invented a new, original, and ornamental Design for a Combined Billfold, Key Case, and Token Purse, of which the following is a specification, reference being had to the accompanying drawing, forming a part thereof wherein:

Figure 1 is a perspective view of a combined billfold, key case and token purse fully opened, showing my new design.

Figure 3 is a perspective view of the combined billfold, key case and token purse completely closed, looking at one side of the same, and

I claim:

The ornamental design for a combined billfold, key case and token purse, as shown.

MILTON BECKER.
